UNITED STATES PATENT OFFICE

WILLIAM D. MCKENDRICK, OF SOUTH PASADENA, CALIFORNIA

POWDER INSUFFLATOR

Application filed March 7, 1928. Serial No. 259,666.

This invention relates to insufflators, and especially to an insufflator whereby a dry powder or like substance may be introduced in the internal passages or cavities of the body.

5 The object of the present invention is to generally improve and simplify the construction and operation of powder insufflators. To provide an insufflator which is adapted to be charged from a bulk supply with a dry powder-like substance containing drugs, anti-septics, etc., and inserted in the internal passages or cavities where the powder is to be applied. To provide means for discharging and uniformly distributing the powder by means 10 of an air blast after insertion of the insufflator; and further to provide a syringe which may be readily and quickly charged and also taken apart for cleaning, etc.

20 The syringe is shown, by way of illustration, in the accompanying drawing, which shows a side elevation of the insufflator partially in section.

25 Referring to the drawing in detail, A indicates a tube constructed of metal or like material. One end of the tube is designed to receive and retain a bulb B while the opposite end is slightly expanded to form a nozzle-head C. The nozzle-head is provided with an internally threaded section 3 to receive and support a nozzle such as indicated at 8. The 30 nozzle-head is also provided with an internally threaded extension 4, the exterior diameter of which is smaller than the interior diameter of the nozzle. Two or more openings 4^a are formed at the base of the threaded extension 4 and these openings permit air to escape from the tube A into the annular space 4^b formed between the exterior surface of the extension 4 and the interior surface of the nozzle. The extension 4 forms a receptacle and a holder for a plug, generally indicated at 5, the plug being provided with a threaded extension 7 which is adapted 40 to be screwed into the extension 4. The outer end of the plug fits the interior diameter of the nozzle 8 and it is provided with one or more helical grooves such as indicated at 6, which serve the function of distributing the 45 air discharging from the tube A into the an-

nular passage 4^b. The forward end of the nozzle is provided with a discharge opening 9 but this is normally closed by means of a friction cap 10.

In operation the insufflator is charged as follows:

55 The nozzle 8 is first unscrewed and removed and the friction cap or closer 10 is applied. The nozzle is then filled with the disinfectant, or whatever the case may be, in a powder-like form from a bulk supply, or otherwise, 60 and it is replaced on the nozzle-head C by screwing it into the threaded extension 3. When the syringe is to be used the friction cap 10 is removed and the nozzle is inserted 65 in the internal passage or cavity to be treated. When inserted the bulb B is depressed or squeezed by hand pressure and air will thus be discharged through the tube A and the openings 4^a into the annular passage 4^b. 70 The air then escapes into the nozzle through the helical grooves 6. As the air discharges around and through the helical passages it is evenly distributed within the nozzle 8 and as such discharges all the powder through 75 the nozzle opening 9. The powder will furthermore discharge with a swirling-like movement and as such is uniformly distributed and applied to the parts to be treated. The insufflator may then be removed for re-charging or cleaning, as the case may be. 80

85 The bulb B may be constructed in any suitable manner. That is, it is the usual type, provided with a valve 11 at one end. This valve closes when the bulb is squeezed or compressed, thus discharging the air outwardly through the tube A. Conversely it opens and refills the bulb when the bulb is released and expands.

90 Any detail showing on the bulb and the valve mechanism employed is thought unnecessary, as a standard structure is employed.

95 While a more or less specific form of air distributing plug is illustrated, I wish it understood that the structure thereof may be considerably modified, as the object of the plug is that of retaining the powder; that is, preventing it from working rearwardly or downwardly through the tube, and that of uniformly delivering or distributing the air 100

so that complete discharge of the powder will take place when the bulb is squeezed; and while other features of the invention are more or less specifically described and illustrated, I wish it understood that changes may be resorted to within the scope of the appended claims. Similarly, that the materials and finish in the several parts employed may be such as the judgment of the manufacturer may dictate or varying conditions or uses may demand.

I claim—

1. In a powder insufflator, a nozzle-head, a nozzle detachable with relation thereto, a tubular extension within the nozzle-head, a plug detachable with relation thereto and substantially fitting the interior of the nozzle, said tubular extension having an exterior diameter smaller than the interior diameter of the nozzle to form an annular air receiving passage, said tubular extension having openings formed therein in communication with a source of air supply, and a plurality of helical shaped ribs formed on the exterior 25 of the plug to impart a swirling motion to air discharging from the annular passage.

2. In a powder insufflator, a nozzle-head, a nozzle detachable with relation thereto, a tubular extension within the nozzle-head, a plug 30 detachable with relation thereto and substantially fitting the interior of the nozzle, said tubular extension having an exterior diameter smaller than the interior diameter of the nozzle to form an annular air receiving 35 passage, said tubular extension having openings formed therein in communication with a source of air supply, a plurality of helical shaped ribs formed on the exterior of the plug to impart a swirling motion to air discharging 40 from the annular passage, and a friction cap removable with relation to the nozzle.
